UNITED STATES PATENT OFFICE

155,659

DESIGN FOR A GAME BOARD

Adolph A. Van Compernolle, Kansas City, Mo.

Application February 9, 1948, Serial No. 144,365

Term of patent 7 years

(Cl. D34—5)

To all whom it may concern:

Be it known that I, Adolph A. Van Compernolle, a citizen of the United States, residing at Kansas City, in the county of Jackson and State of Missouri, have invented a new, original, and ornamental Design for a Game Board, of which the following is a specification, reference being had to the accompanying drawing, forming a part thereof.

Fig. 2 is an edge view of the game board.

I claim:

The ornamental design for a game board, as shown.

ADOLPH A. VAN COMPERNOLLE.
